POUR COUNTER FOR LIQUOR BOTTLES

William J. Miller, Jr., Denver, Colo., assignor of one-third to William Matthew Robertson and one-third to William Harold Ohruh, both of Denver, Colo.

Application October 29, 1951, Serial No. 17,147

Term of patent 14 years

(Cl. D58—10)

To all whom it may concern:

Be it known that I, William J. Miller, Jr., a citizen of the United States of America, residing at Denver, in the county of Denver and State of Colorado, have invented a new, original, and ornamental Design for a Pour Counter for Liquor Bottles, of which the following is a specification, reference being had to the accompanying drawing, forming a part hereof.

Fig. 1 is a perspective view of a pour counter for liquor bottles, showing my new design;

Fig. 2 is a left side view thereof;

Fig. 3 is a front view thereof; and

Fig. 4 is a rear view thereof.

The right side is identical to the left side illustrated in Fig. 2.

I claim:

The ornamental design for a pour counter for liquor bottles, as shown and described.

WILLIAM J. MILLER, JR.
